UNITED STATES PATENT OFFICE.

JOHN SALMON, OF LIVERPOOL, ENGLAND.

TABLE-TENNIS NET.

SPECIFICATION forming part of Letters Patent No. 699,980, dated May 13, 1902.

Application filed February 12, 1902. Serial No. 93,694. (No model.)

To all whom it may concern:

Be it known that I, JOHN SALMON, provision merchant, a subject of the King of Great Britain, residing in Liverpool, in the county 5 of Lancaster, England, (whose full postal address is 23 Temple street, Liverpool,) have invented certain new and useful Improvements in Table-Tennis Nets, of which the following is a specification.

This invention has for its object a cheap and simple form of table-tennis net which will pack up into a small compass and when in use adjusted to any size of table and which will also have the advantage of being resili- 10 ent and yet capable of standing upright on the table without binding-screws, clips, or other like devices. Flexible nets have hitherto required clips or binding devices to hold them upright, and these are liable to dent the 15 table or be otherwise inconvenient. The present invention avoids this defect.

The accompanying drawing is a perspective view of a table-tennis net constructed in accordance with my invention.

Referring to the figure, A is a woven or knotted network made of twine or cord or like material, so as to be flexible, and I support this net in a metallic frame B, with legs C so arranged as to enable the frame with its net 20 to stand upright. The net is by preference made in two lengths placed together end to end, or for a narrow table they can be arranged to overlap. The frames each consist of a piece of metal bent upward at the two 25 ends, the horizontal part b' forming the net-bottom and the turned-up ends b the two uprights for the net A to be secured to. The elasticity of the turned-up ends is adapted to keep the network A taut. The feet C are

simply pieces of metal coiled around the horizontal part b' and projecting on opposite sides, with pieces of rubber D fixed to the end of the feet, which make the nets still more rigid and avoid injury to a polished surface. These feet can be made to raise the net sufficiently to 45 allow the balls to roll underneath from either side, so as to avoid the necessity of throwing the balls back over the net. The top edge of the net is provided with a white tape E, whereby a direct line of sight is obtained, and, furthermore, this top edge E may, if desired, be made 50 elastic, so as to give more easily to the balls; but this is not essential.

By the present invention I do not interfere in the least with the rigidity of the net A, 55 which enables it to stand upright on its feet without being gripped on the table, and yet the cord portion of the net provides the necessary resilience or flexibility, which enables it to give should a ball strike its upper edge, 60 and deliver the ball into the opposite court, while in no way injuring or destroying the ball.

I declare that what I claim is—

A table-tennis net, having the combination 65 of a horizontal metallic bar bent upward at the ends to form posts, feet secured to said horizontal bar, and a flexible network secured at each end to and kept taut by said uprights, substantially as described. 70

In witness whereof I have hereunto signed my name, this 1st day of February, 1902, in the presence of two subscribing witnesses.

JOHN SALMON.
